METHOD AND APPARATUS FOR DIELECTRIC HEATING

George E. Gard, Lancaster, Pa., assignor to Armstrong Cork Company, Lancaster, Pa., a corporation of Pennsylvania

Application October 10, 1946, Serial No. 702,559

16 Claims. (Cl. 219—47)

1

This invention relates broadly to the art of dielectric heating, i. e., the heating of a mass of dielectric material by subjecting it to a high-frequency alternating electric voltage or field between a pair of spaced electrode plates on opposite sides of the mass. More particularly, the invention relates to a dielectric heating system having provisions for (1) heating the electrode plates in order to avoid cooling of the portions of the dielectric mass adjacent thereto and thereby permit the mass to be heated to substantially the same temperature throughout; (2) determining the temperature of the interior of the mass as it is heated; (3) controlling the high-frequency power supplied to the electrode plates so that the dielectric mass is heated at the same rate as the plates; and (4) cutting off the high-frequency power as soon as the mass has reached a predetermined temperature.

In the processing of certain material, i. e., cork granules having a heat activatable binder applied thereto, confined within a mold between electrode plates, by dielectric heating, it has been found that the mass of material is not heated to the same temperature throughout because of heat losses from the outer portions by conduction to the walls of the mold and the electrode plates. As a result, the outer portions of the mass are not as well cured as the interior. The density of the finished product varies because of the temperature differential and such variations lower the quality of the final product, e. g., sheets for the manufacture of gaskets or the like.

I have invented an apparatus and method for processing dielectric materials whereby differences between the temperatures of the interior of the mass and the outer portions thereof are minimized with the result that a more uniform cure is obtained and the finished product exhibits substantially uniform density. In a preferred embodiment and practice of the invention, I heat the electrode plates from an external source to prevent them from absorbing heat from the outer portions of the mass of dielectric and thereby chilling the latter. The electrode plates are conveniently provided with external heaters of any suitable type, preferably electric-resistance or radiant heaters. The electrode plates have a certain thermal capacity and consequently a definite time is required to heat them to a given temperature. The heating of a dielectric mass by the dielectric effect, however, is almost instantaneous because heat is generated uniformly throughout the mass and no

2

time is required for heat transfer or flow. In order to assure that the heating of the mass shall proceed as rapidly as possible so as to attain a short curing cycle and yet not outrun the heating of the plates (which would give rise to the objectionable non-uniform cure mentioned above), I utilize the temperature of the plates as a check in controlling the application of high-frequency power to effect dielectric heating of the mass. In other words, I heat the plates as rapidly as possible and restrain the heating of the mass so that its temperature in rising keeps pace with that of the plates.

My invention thus differs from a previous proposal to control the heating of the electrode plates in accordance with the temperature attained by the mass of dielectric material. This procedure is wholly impractical for certain applications since the thermal lag of the electrode plates may be longer than the complete curing cycle for some materials. Due to the relatively large thermal capacity of the electrode plates, when heating them either by electric heaters or any other means, they require a relatively long time interval to attain a given temperature. On the other hand, as stated above, heating by dielectric effect is almost instantaneous. It is thus not possible to maintain uniform temperature throughout the dielectric mass by any conceivable means of varying the power input into the electrode plates in accordance with the temperature of the mass.

Specifically, my invention includes means for controlling the average power output of the source of high-frequency voltage used to effect dielectric heating in accordance with the temperature of the electrode plates. That is to say, the rate at which the temperature of the electrode plates rises is utilized as a limit on the rate at which the temperature of the mass of dielectric material is raised so that uniform temperature conditions throughout the latter may be maintained. This arrangement allows the temperature rise in the dielectric mass to proceed at the same rate as the temperature rise in the electrode plates, thereby maintaining a uniform temperature rise throughout the mass of dielectric material.

In order to control the rate of heating of the dielectric mass, I provide electrical means for measuring the temperature at the interior thereof and control the power input to the mass accordingly. This may be done manually although I prefer automatic temperature-responsive means. I also employ temperature-respon-

sive means to terminate the application of the alternating electric field when the temperature of the dielectric mass has reached the desired final value.

Dielectric heating has been conducted heretofore on a time-controlled basis, on the assumption that the material being heated is uniform with respect to moisture content, percentage of binder, and other factors influencing the rate of heating. Such a procedure may require exact formulation of mixes and storage of material prior to heating in air-conditioned space, otherwise the final temperature attained in a fixed time interval may vary, for example, because of non-uniform moisture content of the material. According to the method of my invention, I eliminate all these variables by merely continuing to heat the mass by the dielectric effect, regardless of the time, until the desired final temperature is reached, whereupon I discontinue the supply of high-frequency power to the mass and permit it to cool. In this connection, it is to be noted that the rate of temperature rise of the mass, in some materials, is quite high toward the end of the heating stage. It thus becomes very important to avoid overshooting of the temperature and the resultant injurious effect such as overcuring or charring.

One of the electrode plates used in dielectric heating is usually grounded while the other is at a potential above ground which may be several thousand volts, depending on the character of the material being processed and the alternating electric stress which it is desired to establish therein. This presents a serious problem in making connections to the electric heater for the high-voltage electrode plate because of the difficulty of isolating the high-frequency voltage from the circuit supplying current to the heater for the electrode plate. I overcome this difficulty by employing a tuning coil formed of tubular conductor, connected in parallel with the electrode plates and the mass of material therebetween, the electrical constants of the circuit being adjusted to provide parallel resonance when the circuit is connected to a current source of appropriate high frequency such as 10 megacycles. Because of the high frequency employed, the current in the tuning coil flows exclusively in the outer layers thereof due to skin effect, thus leaving the heater-supply circuit on the interior entirely isolated. I also provide electrical temperature-indicating and control means for the high-voltage plate and the mass of material being heated and bring the leads therefrom out through the interior of the tubular conductor forming the tuning coil.

A complete understanding of the invention may be obtained from the following detailed description and explanation which refer to the accompanying drawings illustrating a preferred embodiment of the apparatus. In the drawings,

Figures 1A and 1B together constitute a diagrammatic view showing a mold for confining the mass of material to be heated in vertical section, the tuning coil and control system for the source of high-frequency alternating voltage;

Figure 2 is an enlarged central section through a tube adapted to be inserted into the mass of material, having temperature-responsive means therein;

Figure 3 is a portion of Figure 1A to enlarged scale; and

Figure 4 is a partial diagrammatic view similar to a portion of Figure 1A, showing a modification.

Referring in detail to the drawings, a mold 10 in the form of a box open at the bottom and top is composed of wood side walls 11 having upper and lower binding frames 12 of angle iron. The wood walls of the mold are preferably impregnated with ceresin wax to give them a dielectric loss factor greater than that of the material to be processed. A method of dielectrically heating material utilizing a mold having a higher loss factor than the material to be processed is disclosed and claimed in the copending application of George E. Gard, Serial No. 678,217, filed June 21, 1946, and entitled "Method of compensating for or preventing heat losses from material during dielectric heating thereof." This affords compensation for heat losses to the walls which would otherwise occur. Electrode plates 13 and 14 form removable top and bottom walls for the mold, serving to confine therebetween a mass of dielectric material 15, e. g., cork granules having a heat activatable binder thereon. Upper and lower peripheral conductors 13a and 14a extend around the mold and are electrically connected to the plates 13 and 14, respectively, by jumper strips 13b and 14b. These conductors serve to create a more intensive field within the mold walls than is created in the mass and serve to compensate for heat losses from the mass to the mold walls. This is more fully disclosed and claimed in the copending application of George W. Scott, Jr., Serial No. 678,214, filed June 21, 1946.

Each of the plates 13 and 14 is maintained in position by a pair of pins 16 extending through aligned holes in opposite side walls of the mold. The plates 13 and 14 have covers 17 and 18 engaging the outer surfaces thereof. The pins 16 bear on the covers 17 and 18. The construction of the mold as thus far described, except for the covers 17 and 18, is also disclosed and claimed in a copending application of George W. Scott, Jr., Serial No. 678,215 filed June 21, 1946.

High-frequency alternating voltage is applied across the plates 13 and 14 from any convenient source, to establish the alternating electric field in the mass 15 necessary to heat it by the dielectric effect. A known type of thermionic oscillator indicated at 19 serves as a convenient source of high-frequency current. The oscillator output is applied to a circuit tuned to parallel resonance including the mass 15 which forms a condenser with the plates 13 and 14, and an inductance composed of a conductor of suitable character, such as a tuning coil 20. One side of the oscillator output circuit is connected through the contacts of a shut-off contactor 21 and a supply line 22 to an adjustable contact 23 engaging the coil 20. The other side of the oscillator output circuit is grounded at 24. One end of the coil 20 and the plate 14 are similarly grounded at 25.

As illustrated, the tuning coil 20 is a helix formed from a tubular conductor, e. g., copper tubing. In a specific embodiment, $\frac{1}{2}$ " copper tubing having a wall thickness of .035" was used. The upper end of the coil has a flexible lateral extension 26 connected to the cover 17. The tubular conductor is flanged at its end and is secured to a boss 27 on the cover 17 by a collar 28. The cover 17 being of metal and in contact with the plate 13 under the pressure exerted by the confined mass 15, provides a good electrical connection from the extension 26 to the plate. A grounded shield S of wire mesh encloses the mold 10 and coil 20.

Electric heaters 29 of the radiant type are mounted on the outer faces of the plates 13 and

14 for the purpose of heating the latter to prevent loss of heat from the top and bottom portions of the mass 15 as its temperature increases on heating by the dielectric effect. The heaters may be of any desired construction. As illustrated, they comprise simply a coil of resistance wire wound on a support which may conveniently be a metal strip sheathed with suitable insulation. Any desired number of such heaters may be mounted on each electrode plate. Current is supplied to the heaters on the plate 14 through leads 30 extending outwardly through a hole 31 in the cover 18 and a shielding tube 31a depending therefrom. The leads 30 are connected through a switch 32 to a source of current 33 of ordinary voltage and frequency, i. e., 220 volts, 60 cycles. Heating current is similarly supplied to the heaters on plate 13 through leads 34. These leads, in the form of insulated conductors, extend into and through the tubular conductor forming the coil 20 and enter the cover 17 through the boss 21. Since the high-frequency current in the coil 20, the cover 17 and plate 13 is confined to the exterior of these parts, substantially infinite impedance exists between the parallel resonance circuit and the conductors 34 supplying the heaters 29 of the plate 13, the potential of which is several thousand volts above that of the ground to which the plate 14 is connected, when the oscillator is operated.

I provide means responsive to the temperature to which the plate 13 is heated by the heaters 29, in order to control the power output of the oscillator (which is the same as the power input to the mass 15) so that the latter will be heated up at substantially the same rate as the plates. I provide the plate 13 with a thermocouple 35 as shown in Figure 3. Leads 36 from the thermocouple are brought out through the tubular conductor forming the coil 20 and are connected to an indicating device 37 such as a millivolt meter. I also provide the plate 13 with a resistor 38 as a further means for obtaining the temperature of the plate. A lead 36' extends therefrom through the tubular conductor forming the tuning coil. The resistance of the resistor 38 increases directly with the temperature and may thus be used to actuate an indicator or controller in accordance with the temperature of the plate 13. The resistor is connected to a controller (referred to hereinafter) by the lead 36'. The hot junction of the thermocouple 35 and the resistor 38 are both connected to the plate 13.

The plate 14 also has a thermocouple 35 for temperature indication connected by leads 40 to a millivolt meter 41.

In order to compare the temperature of the mass 15 as it rises to the desired maximum value with the temperatures of the plates 13 and 14, I provide a thermo-responsive element in the form of a fine tube 42 closed at one end, adapted to be inserted through one of a plurality of holes 43 in one of the side walls of the mold 18 and to extend inwardly of the mass 15 to a point adjacent the center thereof. A thermocouple 44 and control resistors 45 and 45' are disposed in the tube 42 adjacent to the closed end as shown in Figure 2. Leads 46 from the thermocouple and leads 47 and 47' from the resistors pass through a flexible and extensible conducting case 48 branching from the tubular conductor forming the coil 20. The copper lead from the couple 44 serves as the common return for resistors 45 and 45'. The case 48 may conveniently be of bellows-like construction. The tube 42 is preferably in-

serted so that it lies in the median transverse plane through the mass 15 and parallel to the plates 13 and 14. Under these conditions, if the case 48 is connected to the mid-point of the coil 20, the potential at the end of the tube 42 will be the same as that on the point of the coil 20 to which the case 48 is connected, since the voltage gradient across the mass 15 is the same as that across the coil 20, and there will be no flow of current which would heat the tube and thermo-responsive means and cause the indication of the thermo-responsive means to be high. The tube 42, of course, may be inserted in the mass at any desired transverse plane if the point of connection of the case 48 to the coil 20 is made to correspond so as to balance the voltage on the two sides of the electrical bridge composed of the capacities between the tube 42 and the plates 13 and 14 on the one side, and the portion of the coil 20 above and below the point of connection of case 48 thereto, on the other side. To insure this balanced condition, I provide an indicator such as a lamp 49 or other indicating device connected across a portion of the length of the case 48. Thus if any difference of potential exists along the latter, the lamp 49 will be illuminated. In such case, the position of the tube 42 would be altered until a balanced condition is obtained. It is for this purpose that a plurality of holes 43 are provided in the side wall of the mold.

The leads 46 from the thermocouple 44 are brought out through the lower half of the coil 20 and are connected to a millivolt meter 50, thus giving a ready comparison between the temperature at the center of the mass 15 and the temperatures of the plates 13 and 14.

In a preferred practice of the method of my invention, the mold 18 is filled with a charge of material to be processed, the plate 13 and cover 17 being removed to permit filling of the mold. This may readily be accomplished by withdrawing the upper pins 16 and lifting the cover 17 and plate 13, the plate 14 being left in position. When the mold has been filled, the charge is compressed and the plate 13 and cover 17 replaced, after which the charge is held under pressure by insertion of the pins 16. The charge is then ready to be heated dielectrically to cure the heat-activatable binder on the cork granules forming the charge.

The tube 42 having been inserted through the mold wall into the mass 15, the switch 32 is closed to energize the heaters 29. The plates 13 and 14 are thereby heated and their temperature begins to rise slowly, being indicated on the meters 37 and 41. At this time, the oscillator 19 is connected across the tuning coil 20 by closing the contactor 21. Heating of the mass 15 by the dielectric effect is thus initiated and the temperature existing at the center of the mass is indicated on the meter 50. The average output of the oscillator 19 is controlled by a power regulator 51 in such manner that the temperature rise in the mass 15 follows that of the plates 13 and 14 as closely as possible. As a result of this procedure, the plates 13 and 14 do not absorb any heat from the mass 15 and the temperature of the top and bottom of the latter rises at the same rate as the interior thereof, thus effecting a uniform curing of the binder throughout the mass. When the temperature at the center of the mass 15 has been raised to the desired value, the contactor 21 is tripped to disconnect the oscillator from the tuning coil and the switch 32 is opened. On withdrawal of the tube 42, the

mass 15, now fully cured, may be removed from the mold.

It will be observed that the processing described is not time-controlled but is governed solely by the heating of the mass to the desired final temperature which is accurately measured and is substantially uniform throughout the mass. The proper curing of the mix is thus insured regardless of variable factors such as atmospheric temperature and humidity which cannot be accurately controlled except at considerable expense.

The average output of the oscillator or input to the resonant circuit may be controlled in several ways, of which the following are examples. The voltage on the plate of the oscillator tubes may be varied by means of an auto-transformer in the input side of the rectifier supplying the plate voltage in order to control the output power of the oscillator. A grid-controlled rectifier also allows the voltage applied to the plate of the oscillator tubes to be varied, thereby controlling the oscillator output power. A further method of control is by "keying," i. e., negatively biasing the grid of the oscillator tubes by a vacuum tube switch so that the plate current of the oscillator is blocked for a portion of each cycle thereby altering the average power delivered. Finally, the oscillator may be coupled to the resonant circuit or load inductively or capacitatively, and the power delivered to the latter may be controlled by varying the coupling.

In order to facilitate the processing as just described, I may employ automatic control devices including a differential temperature controller 52 and a straight temperature controller 53. These devices are of known construction and are available on the open market. The controller 52 operates to close one contact when one of two temperatures being measured is above the other and to close another contact when the first temperature is below the second. The controller 53 closes a contact when the temperature under measurement reaches the value for which the controller is set. Leads 36' and 47 extend from the resistor 38 and the resistor 45, respectively, through the tubular conductor of coil 20, to the controller 52. The lead 47' connected to the resistor 45' is similarly connected to the controller 53. The electrical resistance thermometers 38, 45 and 45' thus serve to operate the controllers 52 and 53.

The controller 52 operates through a reversing panel 57 provided with suitable relays and a timer for controlling a motor 58. The motor 58 operates the regulator 51 to control the output of the oscillator 19 by any one of the methods outlined above, except the "keying" system which may be controlled directly by the reversing panel 57. In Figure 1B the connections between the several elements, whether electrical or mechanical, are indicated by dotted lines.

The controller 52 functions to cause the regulator 51 to increase the output of the oscillator 19, and the increased output is applied to the mass so long as the temperature at the center of the mass 15 is below that of the plate 13, and to reduce the oscillator output whenever the temperature at the center of the mass exceeds that of the plate. In the "keying" system, the controller 52 and reversing panel 57 will effect a negative biasing of the grids of the oscillator tubes and this will prevent the system from oscillating so long as the negative biasing exists. The timer incorporated in the panel 57 causes the controller 52 to be effective only during predetermined time intervals, e. g., intervals of a few sec-

onds with inactive periods of the same length therebetween. This "on-and-off" action of the controller tends to prevent over-correction and hunting. The timer may be a simple motor-driven contact-making device connected in series with the reversing relays and the contacts of the controller 52.

As previously indicated, the controller 53 serves to trip the contactor 21 and cut off the oscillator from the tuning coil when the temperature at the center of the mass 15 has risen to the desired maximum value for complete curing of the binder.

In order to permit the use of temperature controllers operating from thermocouples instead of resistance thermometers such as shown at 38, 45 and 45', I provide a modified form of thermo-responsive element 42' shown in Figure 4, with its end in section to enlarged scale. This tube 20 has thermocouples 60 and 61 with their hot junctions welded to its end. A thermocouple (not shown) is also substituted for the resistor 38 on plate 13. The thermocouple leads 62 and 63 are brought out through a flexible case 48' similar to that shown at 48 but having an insulated joint 64 intermediate the ends to prevent the flow of direct current. These leads with the leads from the thermocouple on the electrode plate 13 extend through the tubular conductor forming the coil 20. Since the thermocouples 60 and 61 are in electrical contact with the tube 42', I make the inner end of case 48' separate from the end connected to coil 20, to isolate the thermocouple substituted for the resistance element 38 from the thermocouple 60 which thermocouples are differentially connected to the recorder 52. A condenser 65 of from 5 to 10 microfarads capacity serves to conduct any high-frequency current flowing in the circuit across the two arms of the bridge (the mass 15 and coil 20) but this should be small in any event and zero when proper balance is obtained. The leads from the thermocouple 61 substituted for the resistance element 45' are connected to the temperature controller 53 which serves to trip the contactor 21 in the manner previously described when the temperature at the center of the mass has risen to the desired maximum value.

Instead of an oscillator having one side grounded, I may use the well-known "push-pull" circuit. In that case, the thermo-responsive element 42 would have to be inserted with care so as to be at ground potential. The electrode plates 13 and 14 in such systems would be at substantial voltages above and below ground. The temperature-control leads from the tube 42 would therefore be taken through a grounded shield to the exterior of shield S. The temperature-control and heating-current supply leads for the electrode plates 60 would be taken into opposite ends of the coil 20 and out of the grounded mid-point thereof. If the element 42 should be inserted into the mass 15 at a plane other than the median transverse plane, the leads would then have to be taken out through the coil 20.

It will be apparent from the foregoing that the invention is characterized by numerous advantages of marked importance in the practical application of dielectric heating to industrial processing. In the first place, by comparing the temperature of the mass of material being processed with that of the electrode plates, I am able to heat the mass at substantially the same rate as the plates. The overall heating rate may thus be the maximum consistent with maintaining

uniform temperature conditions throughout the mass during the heating stage of the curing cycle and the length of the cycle is kept at a minimum. Increased efficiency results from utilizing electric heaters operating from an existing supply source for heating the electrode plates because such heaters have an efficiency much higher than that which can be attained in the heating of material by the dielectric effect. The heat which is supplied to the electrode plates by the resistance heaters, of course, prevents them from absorbing from the mass of material the heat generated therein by the dielectric effect.

By the use of a tuning coil composed of tubular conductor and placing therein the leads extending to the heaters for the high-voltage electrodes and the thermocouple and resistance thermometer thereof, it is possible to obtain the temperature of the plate and supply energy to electrical heating means therefor, without making electrical contact with the high-voltage circuit itself. The heating of the electrode plates thus rendered possible permits a uniform curing of the dielectric mass not previously attained, because of the loss of heat from the mass to the electrode plates.

It will be obvious that, instead of maintaining the temperature of the mass of dielectric material substantially the same as the temperature of the electrode plates as the heating proceeds, a differential above or below the plate temperature may be maintained should it be desired that the top and bottom portions of the mass be heated to temperatures higher or slightly lower than that at the center.

Although I have illustrated and described but a preferred embodiment and practice of my invention, it will be recognized that changes in the construction and procedure disclosed may be made without departing from the spirit of the invention or the scope of the appended claims.

I claim:

1. In a method of heating a mass of material dielectrically, the steps including disposing the mass between spaced plates, heating said plates externally, simultaneously applying a high-frequency alternating electric field between said plates from a source of high-frequency voltage to heat said mass internally by the dielectric effect, and controlling the average power output of said high-frequency source to heat the mass dielectrically at substantially the same rate as the rate of heating of said plates.

2. In a method of heating a mass of material dielectrically, the steps including confining the mass in a mold between spaced plates, heating said plates externally, simultaneously applying a high-frequency alternating electric field between said plates from a source of high-frequency voltage to heat said mass internally by the dielectric effect, and controlling the average power output of said high-frequency source in accordance with the temperature of one of the plates.

3. In a method of heating a mass of material dielectrically, the steps including disposing the mass between spaced plates, heating said plates externally to cause the temperature thereof to rise, simultaneously applying a high-frequency alternating electric field between said plates from a source of high-frequency voltage to heat said mass internally by the dielectric effect, and controlling the average power output of said high frequency source in accordance with the temperature rise of one of the plates.

4. In a method of heating a mass of material dielectrically, the steps including confining the mass between spaced plates in a mold composed of material having a higher loss factor than the mass, heating said plates externally to cause the temperature thereof to rise, simultaneously applying a high-frequency alternating electric field between said plates from a source of high-frequency voltage to heat said mass internally by the dielectric effect, and controlling the average power output of said high-frequency source in accordance with the temperature rise of one of the plates.

5. In a method of heating a mass of material dielectrically, the steps including disposing the mass between spaced electrode plates, inserting into said mass an element responsive to the temperature of said mass, which element is electrically coupled to a second element responsive to the temperature of one of said electrode plates, heating said plates externally to cause the temperature thereof to rise, simultaneously applying a high-frequency alternating electric field between said plates from a source of high-frequency voltage to heat said mass internally by the dielectric effect, and controlling the average power output of said high-frequency source in accordance with differences in temperature of said two thermo-responsive elements to heat the mass dielectrically at substantially the same rate as the rate of heating of said plates.

6. The method defined by claim 5 characterized by said element responsive to the temperature of said mass being inserted substantially at the median transverse plane through the mass parallel to the plates.

7. Apparatus for dielectrically heating a mass of material comprising a pair of electrode plates on opposite sides of the mass, an inductance composed of tubular conductor connected across said plates, a source of high-frequency alternating voltage for said inductance, thermo-responsive means insertable into said mass, conductors extending from said means entering said tubular conductor at substantially the mid-point of said inductance and extending through the tubular conductor, and a tubular case extending laterally from said tubular conductor, the conductors from said thermo-responsive means being enclosed in said case.

8. The apparatus defined in claim 7 characterized by means for indicating a difference in voltage between spaced points on said tubular case.

9. Apparatus for dielectrically heating a mass of material comprising a mold for confining the mass, a pair of electrode plates on opposite sides of the mass, an inductance composed of tubular conductor connected across said plates, a source of high-frequency alternating voltage for said inductance, thermo-responsive means insertable into said mass through an opening provided in said mold, conductors extending from said thermo-responsive means entering said tubular conductor at substantially the mid-point of said inductance and extending through the tubular conductor, and a tubular case extending laterally from said tubular conductor, the conductors from said thermo-responsive means being enclosed in said case.

10. Apparatus for dielectrically heating a mass of material comprising a pair of electrode plates on opposite sides of the mass, an inductance connected across said plates, a source of high-frequency alternating voltage for said inductance,

heating means for said plates to cause the temperature thereof to rise, a thermo-responsive means disposed adjacent one of said plates, thermo-responsive means adapted to be disposed in said mass, and means actuated by both said thermo-responsive means for so controlling the average power output of said source as to cause the temperature of the mass to conform substantially to that of said one of said plates.

11. Apparatus for dielectrically heating a mass of material comprising spaced electrode plates, means for heating said electrode plates to cause the temperature thereof to rise, and means for dielectrically heating a mass of material between said plates in accordance with the temperature attained by one of said plates comprising an inductance connected across said electrode plates, a source of high-frequency alternating voltage for said inductance, and thermo-responsive means for controlling the average power output of said source to cause the temperature of the mass to conform substantially to that of one of said plates as the temperature of one of said plates rises.

12. In a method of heating a mass of material dielectrically, the steps including disposing the mass between spaced plates, first heating the top and bottom portions of the mass externally, by heating said plates externally to cause the temperature thereof to rise and continuing heating from said plates to the top and bottom portions of the mass adjacent said plates, then heating the interior of said mass dielectrically at substantially the same rate of rise as the rate of rise of the plates, and continuing to heat the mass substantially uniformly throughout until it has reached a predetermined temperature.

13. Apparatus for dielectrically heating a mass of material comprising a pair of electrode plates on opposite sides of the mass, an inductance connected across said plates, a source of high-frequency alternating voltage for said inductance, heating means for said plates to cause the temperature thereof to rise, thermo-responsive means disposed adjacent one of said plates, thermo-responsive means adapted to be disposed in the mass, means actuated by both said thermo-responsive means for controlling the average power output of said source to cause the temperature of the mass to rise in conformity with the rise in temperature of said plates, and means for interrupting the supply of high-frequency voltage to said plates when the temperature of said mass has reached a predetermined value.

14. In a method of heating a mass of material dielectrically, the steps comprising disposing the mass between spaced plates, heating said plates externally, simultaneously applying a high-frequency alternating electric field between said plates from a source of high-frequency voltage, controlling the average power output of said

high-frequency source to heat the mass dielectrically at substantially the same rate as the rate of heating of said plates, and discontinuing the application of external heat to the plates and the application of the field to the mass when the temperature of the mass has reached a predetermined value.

15. Apparatus for dielectrically heating a mass of material comprising a pair of electrode plates 10 on opposite sides of the mass, an inductance composed of a tubular conductor connected across said plates, a source of high-frequency alternating voltage for said inductance, thermo-responsive means insertable into said mass, conductors 15 extending from said means entering said tubular conductor at substantially the mid-point of said inductance and extending through the tubular conductor, and a tubular case for said thermo-responsive means, said case comprising two sections 20 having an insulated joint therebetween to prevent the flow of direct current therethrough and a condenser connected across said sections to conduct any high-frequency alternating current flowing in said sections.

25. 16. Apparatus for dielectrically heating a mass of material comprising a pair of electrode plates for disposition on opposite sides of the mass connected to a source of high-frequency alternating voltage, heating means for said plates to cause 30 the temperature thereof to rise, a thermo-couple disposed adjacent to one of said plates, a second thermocouple disposed in the mass between said electrode plates, and means responsive to a difference in temperature between said thermocouple adjacent to said plate and said thermocouple disposed in the mass for controlling the 35 average power output of said source to cause the temperature of the mass to rise substantially in conformity with the rise in temperature of 40 said plates.

Certificate of Correction

Patent No. 2,508,382

May 23, 1950

GEORGE E. GARD

It is hereby certified that errors appear in the printed specification of the above numbered patent requiring correction as follows:

Column 3, line 26, for "ery" read *very*; column 11, line 60, after the word "voltage" insert a comma;

and that the said Letters Patent should be read with these corrections therein that the same may conform to the record of the case in the Patent Office.

Signed and sealed this 15th day of August, A. D. 1950.

[**SEAL**]

THOMAS F. MURPHY,
Assistant Commissioner of Patents.
